PHOTOTUBE MULTIPLIER

Lozure G. Wolfgang, Bluffton, Ind., assignor, by
mesne assignments, to Farnsworth Research
Corporation, a corporation of Indiana

Application May 29, 1944, Serial No. 537,953

11 Claims. (Cl. 250—175)

1

This invention relates to electron multipliers and particularly to multipliers suitable for use in conjunction with phototubes.

It is customary to employ phototubes for the purpose of translating light energy into electrical energy. The translating elements which have been used are incapable of developing electrical effects of any substantial magnitude in response to light incident upon the translating elements. It, therefore, is necessary to employ in conjunction with the phototube, a means for amplifying or increasing the magnitude of the generated electrical effects in order that they may be utilized. One convenient device for effecting such an amplification is an electron multiplier. In cases where the photosensitive element of the device has a relatively small electron emissive area, the electron multiplier may be located at a point adjacent one of the peripheral edges of the photosensitive element. Such devices have been found to give completely satisfactory results.

However, as is well known in the art, the effectiveness of an electron multiplier is a function of the distance by which it is removed from the primary source of electron emission and the electron accelerating voltage impressed between the multiplier and the emission source. This characteristic, therefore, places certain limitations upon the conventional arrangement of an electron multiplier with respect to the electron emitting cathode of a phototube. It generally is desirable to use accelerating voltages which do not exceed certain predetermined magnitudes. Accordingly, for any given accelerating voltage the distance between the emission source and the multiplier for satisfactory effectiveness is limited.

There are many instances where it is desirable that the phototube be provided with a cathode of considerable surface area. Consequently, there is a substantial portion of the cathode area which is so remote from an electron multiplier of the prior art type referred to that it is impossible to utilize the emission from these remote portions by means of accelerating voltages of reasonable magnitude. In this manner the purpose of such a phototube multiplier is defeated, at least in part.

It is an object of the present invention, therefore, to provide a phototube multiplier in which substantially all of the electron emission from a photosensitive cathode of considerable area is utilized for multiplication without the use of electron accelerating voltages in excess of reasonable magnitudes.

In accordance with the instant invention there is provided a phototube multiplier comprising a photosensitive cathode having a centrally disposed aperture. There also is provided a secondary electron emissive multiplier electrode having a portion disposed in the space contiguous to the

2

photosensitive surface of the cathode and in alignment with the cathode aperture. An electron collecting electrode is disposed in the space contiguous to the opposite surface of the cathode so that it is in communication with the multiplier electrode through the cathode aperture.

For a better understanding of the invention, together with other and further objects thereof, reference is had to the following description, taken 10 in connection with the accompanying drawing, and its scope will be pointed out in the appended claims.

In the drawing:

Fig. 1 is a longitudinal sectional view of a 15 phototube multiplier embodying the invention in one form;

Fig. 2 is a transverse sectional view of the 20 phototube multiplier taken on the line 2—2 of Fig. 1;

Fig. 3 is a longitudinal sectional view of a 25 phototube multiplier embodying the present invention in an alternative form; and,

Fig. 4 is a longitudinal sectional view of a 30 phototube multiplier embodying the present invention in still another form.

Having reference now particularly to Figs. 1 and 2 of the drawing, the illustrated embodiment of the invention is mounted within an evacuated envelope 11. Adjacent one end of the envelope 35 there is provided a substantially flat photosensitive cathode 12. The electron emissive surface of this cathode faces the adjacent end wall of the tube envelope which is formed of optically plane transparent material, such as glass. The cathode 12 is provided with a centrally disposed circular aperture 13. A screen or wire mesh 14 is supported, in spaced relation to the photosensitive surface of the cathode 12 in a suitable manner such as by a flange 15 formed on the cathode.

An annular first stage multiplier electrode 16, 40 which is provided with an exterior concave secondary electron emissive surface, is mounted in such a manner that a portion thereof extends through the cathode aperture 13 well into the space contiguous to the photosensitive surface of the cathode. The remaining portion of the electrode 16 extends into the space contiguous to the

45 opposite surface of the cathode. In this embodiment of the invention the electrode 16 has the general surface configuration of an hour-glass. There also is attached to the upper edge of the electrode 16 a screen or grid 17 which has a generally cylindrical form so that it substantially completely surrounds the portion of the electrode 50

55 surface extending into the space contiguous to the photosensitive surface of the cathode. The screen is open at the bottom in a plane substantially coinciding with the plane of the cathode aperture 13. The screen 17 is electrically connected to the electrode 16 and is insulated electrici-

cally from the cathode 12 and its associated screen 14. The insulation between the grid 17 and the cathode 12 may be secured by spacing the screen from the edges of the cathode aperture. The electrode 16 and its associated screen 17 may be insulated from the cathode screen 14 by means of a plurality of beads such as 18, made of glass or other suitable insulating material. In this manner the inner portions of the cathode screen 14 may be attached to the insulating beads 18 and thereby secure suitable support.

The third and fifth multiplier stages comprise electrodes 19 and 21 having the same general shape as the first stage electrode 16. The electrodes 16, 19 and 21 are disposed axially with respect to the cathode aperture 13 and perpendicularly to the plane of the cathode 12.

The second, fourth and sixth multiplier stages comprise electrodes 22, 23 and 24. Each of these electrodes is annular and is provided with an interior concave secondary electron emissive surface. These electrodes are disposed coaxially with the series of exterior concave surfaced electrodes. The electrodes 22 and 23 are arranged to surround a portion of the space contiguous to the adjacent surfaces of the successive exterior concave surfaced electrodes 16 and 19. Similarly, the electrode 23 surrounds the space contiguous to the adjacent surfaces of the electrodes 19 and 21. The electrode 24 surrounds the space contiguous to the other end portion of the electrode 21 and also the space contiguous to an electron collecting electrode 25. This latter electrode is provided with a substantially flat surface and is mounted coaxially with the multiplier electrodes with its collecting surface parallel to the cathode 12.

The electrodes 19, 21, 22, 23 and 24 are each provided with a cylindrical screen such as 26, 27, 28, 29 and 31, respectively. Each of the screens is electrically connected to its associated multiplier electrode and is interposed between the respective electrodes and the immediately preceding electrode.

Electrical connections to the cathode and to the multiplier electrodes are made through the press portion of the tube envelope 11 to a conventional source of energy in a well known manner (not shown). If desired, the conductors within the tube envelope may be made of sufficiently heavy gage wire to serve also as the mechanical supports for the associated electrodes in a manner well known in the art.

Having reference now to the operation of the form of the invention illustrated in Figs. 1 and 2, before considering the other modifications of the invention, it is assumed that light coming from above as viewed in the drawing impinges upon the photosensitive surface of the cathode 12. Electrons thus are emitted from the upper surface of the cathode at relatively low velocity. In accordance with well known practice the first stage multiplier electrode 16 has impressed thereon a potential of the order of a hundred volts positive with respect to the cathode 12. By reason of the electrical connection of the screen 17 to the multiplier electrode 16, there is created in the vicinity of the screen an electrical field of a strength commensurate with the potential impressed upon the electrode 16. Inasmuch as the screen 17 and a substantial portion of the electrode 16 is located in the space contiguous to the emissive surface of the cathode 12, electrons from all points of the cathode are readily accelerated toward the electrode 16. Thus, the electron accelerating

effectiveness of the first multiplier electrode is so materially increased that a cathode of much greater surface area may be used than in devices of this general character known to the prior art, where the multiplier is located adjacent the peripheral edge of the cathode.

The impingement of the photoelectrons upon the secondary emissive surfaces of the electrode 16 is effected with sufficient velocity to cause the emission by this electrode of increased numbers of secondary electrons. These secondary electrons immediately come under the influence of the field created in the vicinity of the screen 28 associated with the second stage multiplier electrode 22 and are caused to strike the secondary emissive surface of this electrode at sufficient velocity to effect the emission of multiplied numbers of secondary electrons.

The operation of the multistage electron multiplier for succeeding stages is conventional and therefore needs no further explanation. Ultimately, the multiplied stream of electrons is collected by the electrode 25 and may be conducted to a suitable output circuit for utilization.

Having reference now to Fig. 3, there is disclosed a modified form of the invention wherein use is made of a plurality of box-type multiplier electrodes for the higher multiplier stages. The first stage electrode 32 is of the same general character and configuration as the first stage electrode 16 of Fig. 1. Likewise, it is disposed in the cathode aperture 13 in such a manner that a portion of it extends into the space contiguous to the photosensitive surface of the cathode and another portion into the space contiguous to the other surface of the cathode. If desired, this electrode also may be provided with a substantially cylindrical open-bottomed grid 33, electrically connected to the electrode and interposed between it and the photosensitive surface of the cathode.

The second stage multiplier electrode 34 has two opposed openings and a generally hollow configuration and is disposed coaxially with the first stage electrode 32. An electrode similar to the electrode 22 of Fig. 1 may be used or one having a somewhat conical shape as illustrated in Fig. 3 may be satisfactory. The relationship between electrodes 32 and 34 is such that the lower portion of the former extends somewhat inside of the upper opening of the latter. The upper opening of the electrode 34 may be provided with an annular screen 35 electrically connected to this electrode and interposed between the electrodes 32 and 34.

Adjacent the lower opening of the electrode 34, there is disposed the first one 36 of a plurality of conventional box-type multiplier electrodes. In the structure illustrated in Fig. 3, five such electrodes are provided and, communicating with the last one 37 of these electrodes, there is an electron collecting electrode 38. If desired, each of the box-type electrodes such as 36 may be provided with a screen such as 39, mounted at the respective electrode entrances.

The operation of the form of the invention shown in Fig. 3 is substantially similar to the described operation of the apparatus of Fig. 1. Briefly, the photoelectrons emitted by the photosensitive surface of the cathode 12 are accelerated by the first stage screen 33 and electron multiplying electrode 32 so that they are caused to impinge with considerable velocity upon the multiplying electrode. The secondary electrons thus produced are in turn accelerated by the second

stage electrode 34 and its associated screen 35 so as to produce impingement thereof upon the secondary electron emissive surface of this electrode. Further electron multiplication by the succeeding box-like stages is effected in a well known manner.

Still another form of the invention is illustrated in Fig. 4. In this case there is disposed in alignment with the cathode aperture 13 a first stage multiplier electrode 41, the major portion of which extends into the space contiguous to the photosensitive surface of the cathode. This electrode has a conical surface configuration with the apex directed toward the space contiguous to the other side of the cathode 12. The electrode 41 also may be provided with an open-bottomed substantially cylindrical screen 42 interposed between this electrode and the photosensitive surface of the cathode 12.

The first one 43 of a series of box-type electron multiplying electrodes is located so that the entrance opening thereof is in substantial alignment with the cathode aperture 13. Five of such multiplier electrodes are provided, the last one 44 of which has located adjacent its exit opening an electron collecting electrode 45. Each of the box-type multiplier electrodes, such as 42 may be provided with a screen such as 46, located at the respective entrance openings thereof.

The operation of the apparatus illustrated in Fig. 4 is deemed obvious and, therefore, requires no detailed description thereof. As in other forms of the invention, the positioning and configuration of the first stage multiplier electrode 41 insures the acceleration thereto of photoelectrons from any point on the relatively extensive surface of the cathode 12. By reason particularly of the configuration of the electrode 41 there are required no other electrodes of special forms. The remaining multiplier electrodes may be the conventional box-type electrodes as illustrated.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. A phototube multiplier comprising, a substantially flat photosensitive cathode having a centrally disposed aperture, a secondary electron emissive multiplier electrode having a portion disposed in the space contiguous to the photosensitive surface of said cathode and in alignment with said aperture and another portion disposed in the space contiguous to the opposite surface of said cathode, and an electron collecting electrode disposed in the space contiguous to said opposite surface of said cathode and in communication with said multiplier electrode.

2. A phototube multiplier comprising, a substantially flat photosensitive cathode having a centrally disposed aperture, a secondary electron emissive multiplier electrode having a portion disposed in the space contiguous to the photosensitive surface of said cathode and in alignment with said aperture, said electrode having a substantially circular cross sectional area in a plane parallel to the plane of said cathode, a plurality of additional secondary electron emissive multiplier electrodes disposed in the space contiguous to the opposite surface of said cathode and in

communication with said cathode aperture, and an electron collecting electrode disposed in communication with one of said plurality of multiplier electrodes.

3. A phototube multiplier comprising, a cathode having a photosensitive surface and a centrally disposed aperture formed therein, a first annular multiplier electrode disposed axially with respect to said cathode aperture and extending through said cathode aperture into the space contiguous to the photosensitive surface of said cathode and also into the space contiguous to the opposite surface of said cathode, an electron collecting electrode disposed in spaced relation to said cathode on the side opposite to the photosensitive surface thereof, and a second annular multiplier electrode disposed coaxially with said first multiplier electrode and surrounding the space contiguous to that portion of said first electrode extending into the space contiguous to said opposite cathode surface.

4. A phototube multiplier comprising, a cathode having a substantially flat photosensitive surface and a centrally disposed aperture formed therein, a multiplier electrode having an exterior secondary electron emissive surface disposed in alignment with said cathode aperture and having a portion disposed in the space contiguous to the photosensitive surface of said cathode and another portion disposed in the space contiguous to the unsensitized surface of said cathode, a box-type multiplier electrode disposed in the space contiguous to said opposite surface of said cathode in spaced relation to said cathode aperture and in communication therewith, and an electron collecting electrode disposed in spaced relation to said box-type electrode and in communication therewith.

5. A phototube multiplier comprising, a cathode having a photosensitive surface and a centrally disposed aperture formed therein, a first annular multiplier electrode having an exterior concave secondary electron emissive surface disposed axially with respect to said cathode aperture and extending through said cathode aperture into the space contiguous to the photosensitive surface of said cathode and also into the space contiguous to the opposite surface of said cathode, an electron collecting electrode disposed in the space contiguous to said opposite cathode surface, and a second annular multiplier electrode having an interior concave secondary electron emissive surface disposed coaxially with said first multiplier electrode and surrounding the space contiguous to that portion of said first electrode extending into the space contiguous to said opposite cathode surface.

6. A phototube multiplier comprising, a cathode having a photosensitive surface of considerable area and a centrally disposed aperture formed therein, a first plurality of annular multiplier electrodes having exterior concave secondary electron emissive surfaces disposed axially with respect to said cathode aperture, an end one of said first plurality of electrodes extending through said cathode aperture into the space contiguous to the photosensitive surface of said cathode and also into the space contiguous to the opposite surface of said cathode, an electron collecting electrode disposed adjacent to the other end one of said first plurality of electrodes coaxially therewith and having the electron collecting surface thereof parallel to the plane of said cathode aperture, and a second plurality of annular multiplier electrodes having interior concave secondary elec-

tron emissive surfaces disposed coaxially with said first plurality of electrodes, each but one of said second plurality of electrodes surrounding the space contiguous to adjacent surfaces of successive ones of said first plurality of electrodes, said one of said second plurality of electrodes surrounding the space contiguous to the end portion of the other end one of said first plurality of electrodes and also the space contiguous to said collecting electrodes.

7. A phototube multiplier comprising, a substantially flat cathode electrode having a photosensitive surface of considerable area and a centrally disposed aperture formed therein, a first plurality of annular multiplier electrodes having exterior concave secondary electron emissive surfaces disposed axially with respect to said cathode aperture and perpendicularly to the plane of said cathode, an end one of said first plurality of electrodes extending through said cathode aperture into the space contiguous to the photosensitive surface of said cathode and also into the space contiguous to the opposite surface of said cathode, a substantially flat electron collecting electrode disposed adjacent to the other end one of said first plurality of electrodes coaxially therewith and having the electron collecting surface thereof parallel to said cathode, a second plurality of annular multiplier electrodes having interior concave secondary electron emissive surfaces disposed coaxially with said first plurality of electrodes, each but one of said second plurality of electrodes surrounding the space contiguous to adjacent surfaces of successive ones of said first plurality of electrodes, said one of said second plurality of electrodes surrounding the space contiguous to the end portion of the other end one of said first plurality of electrodes and also the space contiguous to said collecting electrode, and a plurality of cylindrical screens electrically connected respectively to said multiplier electrodes and interposed between said respective electrodes and the immediately preceding electrodes.

8. A phototube multiplier comprising, a cathode having a photosensitive surface and a centrally disposed aperture formed therein, a first annular multiplier electrode having an exterior concave secondary electron emissive surface disposed axially with respect to said cathode aperture and extending through said cathode aperture into the space contiguous to the photosensitive surface of said cathode and also into the space contiguous to the opposite surface of said cathode, a second annular multiplier electrode having two oppositely disposed openings and arranged coaxially with said first multiplier electrode with one of said openings surrounding the space contiguous to that portion of said first multiplier electrode extending into the space contiguous to said opposite cathode surface and having an interior secondary electron emissive surface, a box-type multiplier electrode disposed adjacent to the other opening of said second annular electrode, and an electron collecting electrode disposed in spaced relation to said box-type electrode and in communication therewith.

9. A phototube multiplier comprising, a substantially flat cathode electrode having a photosensitive surface of considerable area and a centrally disposed aperture formed therein, a first annular multiplier electrode having an exterior concave secondary electron emissive surface disposed axially with respect to said cathode aper-

ture, perpendicularly to the plane of said cathode and extending through said cathode aperture into the space contiguous to the photosensitive surface of said cathode and also into the space contiguous to the opposite surface of said cathode, a second annular multiplier electrode having two opposed openings and a generally hollow configuration disposed coaxially with said first multiplier electrode with one opening thereof surrounding the space contiguous to that portion of said first multiplier electrode extending into the space contiguous to said opposite cathode surface and having an interior secondary electron emissive surface, a plurality of serially arranged box-type multiplier electrodes, an end one of said plurality of electrodes being disposed adjacent to the other opening of said second annular electrode, an electron connecting electrode disposed adjacent to the other end one of said plurality of box-type electrodes, and a plurality of screens electrically connected respectively to said multiplier electrodes and interposed between said respective electrodes and the immediately preceding electrodes.

10. A phototube multiplier comprising, a cathode having a substantially flat photosensitive surface and a centrally disposed aperture formed therein, a multiplier electrode having a conical exterior secondary electron emissive surface disposed in alignment with said cathode aperture in the space contiguous to the photosensitive surface of said cathode and with the apex of said electrode adjacent to said cathode aperture, a box-type multiplier electrode disposed in the space contiguous to the opposite surface of said cathode adjacent to said cathode aperture, and an electron collecting electrode disposed in spaced relation to said box-type electrode and in communication therewith.

11. A phototube multiplier comprising, a substantially flat cathode electrode having a photosensitive surface of considerable area and a centrally disposed aperture formed therein, a multiplier electrode having a conical exterior secondary electron emissive surface disposed axially with respect to said cathode aperture and perpendicularly to the plane of said cathode in the space contiguous to the photosensitive surface of said cathode and with the apex of said multiplier electrode adjacent to said cathode aperture, a plurality of serially arranged box-type multiplier electrodes disposed in the space contiguous to the opposite surface of said cathode, an end one of said plurality of electrodes being disposed adjacent to said cathode aperture, an electron collecting electrode disposed adjacent to the other end one of said plurality of box-type electrodes, and a plurality of screens electrically connected respectively to said multiplier electrodes and interposed between said respective electrodes and the immediately preceding electrodes.
